(57) **CLAIM**

The ornamental design for a cartridge for vaporizer device, as shown and described.

DESCRIPTION

FIG. 1 is a front perspective view of the cartridge for vaporizer device showing our new design;

FIG. 2 is a rear perspective view of the cartridge for vaporizer device of FIG. 1;

FIG. 3 is a left side elevational view of the cartridge for vaporizer device of FIG. 1;

FIG. 4 is a right side elevational view of the cartridge for vaporizer device of FIG. 1;

FIG. 5 is a bottom plan view of the cartridge for vaporizer device of FIG. 1;

FIG. 6 is a top plan view of the cartridge for vaporizer device of FIG. 1;

FIG. 7 is a front elevational view of the cartridge for vaporizer device of FIG. 1; and,

FIG. 8 is a rear elevational view of the cartridge for vaporizer device of FIG. 1.

The broken lines in the drawings depict portions of the cartridge for vaporizer device that form no part of the claimed design.

1 Claim, 5 Drawing Sheets
